Primary Examiner — Cathy Anne MacCormac(74) Attorney, Agent, or Firm — Quickpatents, LLC; Kevin Prince(57) CLAIM

I claim the ornamental design for a pet toy, as shown and described.

DESCRIPTION

FIG. 1 is a perspective view of a pet toy, showing my new design;

FIG. 2 is a front elevational view thereof;

FIG. 3 is a rear elevational view thereof;

FIG. 4 is a left-side elevational view thereof;

FIG. 5 is a top plan view thereof; and,

FIG. 6 is a bottom plan view thereof.

The broken lines depict environmental subject matter and form no part of the claimed design.
